(57) **CLAIM**

The ornamental design for a barbell pad, as shown and described.

DESCRIPTION

FIG. 1 is a perspective view of a barbell pad showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of a barbell pad shown in a hanging position thereof; and,

FIG. 9 is an exposed front view.

The broken lines in the drawings depict portions of the barbell pad that form no part of the claimed design.
